UNITED STATES PATENT OFFICE.

MORRIS WEHLI, OF BASEL, SWITZERLAND.

GRATING FOR THE LICKER-IN OF COTTON-CARDING ENGINES.

1,409,627.

Specification of Letters Patent. Patented Mar. 14, 1922.

Application filed September 19, 1917. Serial No. 192,160.

(GRANTED UNDER THE PROVISIONS OF THE ACT OF MARCH 3, 1921, 41 STAT. L., 1313.)

To all whom it may concern:

Be it known that I, MORRIS WEHLI, mechanical engineer, a citizen of the United States, residing at Basel, in the Confederation of Switzerland, have invented certain new and useful Improvements in Gratings for the Licker-In of Cotton-Carding Engines, (for which I have made applications for Letters Patent in Switzerland under 10 dates of September 4th and December 29, 1916,) of which the following is a specification.

The present invention relates to a grating for the licker-in of cotton carding engines 15 and in which at the rear of the usual set of adjustable bars there is provided a flat bar which may be adjusted at an angle to the surface of the licker-in and a number of sharply edged knives followed by a plurality of three sided bars, the upper surfaces of which are set at an angle with regard to an imaginary cylindrical surface laid through their edges.

In order to furnish means for adjusting 25 such knives and bars as may be required the said knives and bars may be mounted at their ends in radial slotted bars which are held adjustably in circular slots of supports fixed to the side frames of the licker-in.

30 In the drawing:

Fig. 1 is a cross section illustrating my improved grating where the knives and bars, held in adjustable supports secured to the frame, are fixed in position with regard to 35 each other.

Fig. 2 is a cross section through a grating similar to the one shown in Fig. 1 but with the knives and bars made adjustable with regard to each other, and

40 Fig. 3 is a section on line A—A of Fig. 2.

Referring to the drawing, 1 represents the feed roller, 2 the trough of the same, 3 the licker-in, 4 some of the usual grate-bars, 5 a wide adjustable flat bar, 6 and 7 are 45 sharply edged knives, 8 three-sided grate bars, 9 the usual sheet covering, and 10 the main cylinder.

The cotton fed to carding engines is a lap composed of compact bunches containing 50 foreign matter such as short staple and dust.

In the fleece running out from the collector the single fibres are separated from each other and present a very thin and clear film

containing few but prominent foreign substances.

Therefore the cotton bunches, while traveling from the licker-in to the comb taking the film off the collecting cylinder, have to be thoroughly opened and the cotton separated from foreign substances, short fibres, sand and dust. This opening of the cotton bunches is effected by the toothed surface of the licker-in and of the wire cloth of the main cylinder, the flats and the collector, while the separation from the foreign matter 65 is effected by the centrifugal force of the licker-in and of the main cylinder in coaction with the gratings surrounding the same, and with the interstices between the wires wherein the short staple and foreign substances are collected. In order to make it possible for the fibres thrown off from licker-in and main cylinder to return to the bulk of good staple the grating and sheet covering surrounding the quickly revolving parts 70 have to be adjusted to allow a reduction of the force of the air currents revolving with the licker-in should the compact bunches fly off so as to be dashed against the edges of the grate bars, or if the bunches should be 75 caught by the wires of the opposite working parts so as to have one fibre after the other drawn out from the bunch by the wires of the quicker running working surface. Besides, the grates and coverings have to produce a suction action and a compression of air if the fibres are to be attracted again by the quickly turning working parts.

It will therefore be easily understood that for the licker-in which has to perform the 90 rough opening of the bunches the intensity of the power required is a good deal greater than in the case of the main cylinder, workers and flats which do the finer opening. If the reduction of the force of the air current exceeds the sucking action and the compression 95 the licker-in will be "downing," that is to say much good staple will be retained in it as many of the fibers thrown off cannot return towards the surface of the cylinder and 100 will fall into the waste. The product of the carding engine will thus be diminished to the extent of this waste which means so much loss, as the higher price of the better product improved by the lost staple does not 105 compensate for this loss. Besides the very

light dust will also be aspirated by the cylinder and will adhere to the wire cloth of the main cylinder and flats which when being cleaned causes a dust which is very injurious to health.

The reason for this "downing" or losing good staple and for the dust when cleaning the apparatus in the usual form of licker-in devices is that the knives and following grate bars reduce the air currents passing between the same to such an extent as to cause this action.

The object of my invention is therefore to provide between the usual knives 4 and the following grate bars an adjustable flat bar 5 for facilitating the aspirating action of the licker-in and to have at the rear of this flat bar a number of smaller knives 6, 7 and a final part consisting of three sided bars 8 the surfaces of which face the licker-in 3 and are likewise set at an angle to the surface of an imaginary cylindrical surface laid through the edges of said bars in order to create the greatest possible working cross-section for the action of the air current.

In operation the apparatus works as follows:

Owing to the considerable revolving speed of the licker-in 3 a layer of air circulates with it and is sucked off by the layer of air circulating at least twice as fast with the main cylinder 10. This suction action is facilitated by the hood 9 covering the licker-in and extending from the main cylinder 10 to the feed roller 1, and the edge of which near the main cylinder 10 is set closely against the surface of the licker-in 3 so as to act like a cut-off for the air. The air sucked off by the main cylinder 10 is restored from the atmospheric air through the apertures between the grate bars 4, 5, 6, 7 and 8, and the velocity of this air entering through these apertures will be less as the open surface of grating is increased. But the smaller the velocity, the better the small fibres and particles of dust thrown off by the licker-in will be enabled to settle down in the waste. The larger fibres will be prevented from getting out of reach of the licker-in by the fact that they offer a larger surface to the air current than the smaller ones.

In order to facilitate licker-in 3 in throwing off the foreign substances the edges of the bars 4, 6, 7, 8 are set very closely against the licker-in so as to cause the air circulating with the cylinder to glide off along the surface of bar 5. Immediately behind the edge of this bar a space with rarefied air is formed which will at once be filled again by air passing in along the faces of bars 7 and by this flow of air immediately behind the said edges the fibres clinging like hooks against the wires of the licker-in but running the risk of being thrown off, and being left on the edges of the bars will be pressed

firmly against the surface of the cylinder so as to be drawn along with it. The ends of fibres extending over the edges of the bars while rubbing along these edges will be freed of all particles of dust or husk and the more often this is repeated, that is, the more bars there are, the better this cleaning process of the cotton will be effected. These facts explain the great cleaning capacity of the apparatus made according to my invention.

In the other forms of grating heretofore employed on the contrary the faces of the bars all ran parallel with the surface of the licker-in leaving but small apertures between them thereby causing the velocity of the entering air current to be very considerable.

According to the present invention, however, owing to the wide inlet aperture between the licker-in 3, and flat bar 5, and owing to the wide openings between the knives, the aspirated air will assume a smaller velocity, small enough to allow the settling of the smaller lighter particles. This weaker current, however, will suffice to draw back again the larger staple presenting a larger surface and after having brought it into reach of the licker-in to press the same against the cylinder. Thus in the waste of the licker-in only seeds, particles of stalks and leaves, and a very short down, together with dust and sand will be found, but no good staple, and the staple presented to the main cylinder will be so much better that the wire cloth will be more effective and less dust will collect thereon.

In Fig. 2 the new grating is represented with means for adjusting each bar independently from the other. The flat bar 5 following the usual bars 4 is mounted on a pivot point 51. The knives 7 as well as the bars 8 rest on both sides of the engine within the forked upper ends of the flat bars 17 and 18 while the lower ends of said bars are slotted and fastened by means of bolts 14 to the support 15 curved concentrically to the axis of the licker-in, said support being provided likewise with a curved slot for receiving said bolts. These bolts being slidable in said curved slot permit the adjustment of the grate bars around the periphery of the licker-in, and the slots within the bars 17, 18 permit the adjustment of the grate bars radially with regard to the licker-in, so as to allow of an adjustment of the grate bars and knives to almost any position.

This universal adjustment of the bars has the advantage that the bars may be set independently of each other in every position and makes the bars easily interchangeable. Besides the number of bars may be increased or decreased and the openings between the bars regulated as may best suit the circumstances.

I claim as my invention:

1. In a cotton carding engine and in combination with the licker in and the ordinary front bars associated therewith, a flat bar 5 adjustably mounted at the rear of the said ordinary bars, and a plurality of knives and grate bars at the rear of the said adjustable flat bar.
2. In a cotton carding engine and in combination with the licker in and the ordinary front bars associated therewith, a flat bar 10 at the rear of the said front bars, means for adjusting the said flat bar to position relatively to the surface of the licker in, and 15 a plurality of knives and grate bars at the rear of the said flat bar.
3. In a cotton carding engine and in combination with the licker in and the ordinary front bars associated therewith, a flat bar 20 at the rear of the said front bars, means for adjusting the said flat bar to position relatively to the surface of the licker in, and a plurality of adjustable knives and great bars at the rear of the said flat bar.
- 25 4. In a cotton carding engine and in combination with the licker in and the ordinary front bars associated therewith, a flat bar at the rear of the said front bars, means for adjusting the said flat bar to position 30 relatively to the surface of the licker in, a plurality of adjustable knives and grate bars at the rear of the said flat bar, and means for independently adjusting the said knives and grate bars to position relatively to the surface of the licker in.
5. In a cotton carding engine and in combination with the licker in and the front bars associated therewith, a flat bar at the rear of the front bars, means for adjusting the flat bar to position relatively to the surface of the licker in, a plurality of knives at the rear of the flat bar, a plurality of grate bars at the rear of the said knives, and means for adjustably securing each of the said knives and grate bars to position relatively to the surface of the licker in.
6. In a cotton carding engine and in combination with the licker in and the front bars associated therewith, a flat bar at the rear of the front bars, means for adjusting the flat bar to position relatively to the surface of the licker in, a plurality of knives at the rear of the flat bar, a plurality of grate bars at the rear of the said knives, and means for adjustably securing each of the said knives and grate bars to position relatively to the surface of the licker in.
- In testimony whereof I have affixed my signature in presence of two witnesses.
- MORRIS WEHLI.
